Design U.S. Appl. No. 29/433,240, filed Sep. 27, 2012, Garneau et al.

Primary Examiner — Prabhakar Deshmukh(74) *Attorney, Agent, or Firm* — Nixon & Vanderhye PC(57) **CLAIM**

The ornamental design for a jukebox and stand, as shown and described.

DESCRIPTION

FIG. 1 is a front perspective view of a jukebox and stand showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side view thereof;

FIG. 7 is a left side view thereof; and,

FIG. 8 is a rear perspective view thereof.

The broken lines represent environmental structure and form no part of the claimed design.

1 Claim, 7 Drawing Sheets---
